DOOR HANDLE ASSEMBLY

Emanuel Jaggi, 2 Hoenggerstrasse, Zurich, Switzerland
Filed June 4, 1959, Ser. No. 818,179
5 Claims. (Cl. 292—353)

The present invention relates to a door handle assembly, and has the main object of providing a device for the connection of the connecting bar of a door with the door handles, door knobs or the like in a manner allowing easy assembling and dismantling without the use of a tool.

In most of the devices used for connection of door handles or door knobs to a connecting bar, the latter has at both ends, in its longitudinal center, a serrated slot into which pins pushed through holes of the handles penetrate. Embodiments are also known, in which the bar, usually of a square profile, is provided near the ends at one of its faces with serrations into which engages a spring, a pawl or a pin. The embodiment having pawls is complicated and involves the use of screws having conical heads, while the spring is pressed by a screw or the like from outside into the serrations.

In all known devices of this kind the door handles or the like must be drilled through for the insertion of screws or pins. As is well known, this involves the danger that the screws or pins may work loose as a result of many pulls upon the handles or the like, and may even drop off and so get lost. When the screws and pins are secured by riveting or in a similar way, dismantling becomes extremely difficult, and in any case is impossible without the use of tools.

All these disadvantages are overcome by the present invention, according to which I provide a door handle assembly, comprising in combination: a pair of door handles each having a stem provided with a bore and at least one row of serrations in the said bore, a connecting bar having serrations upon one face thereof complementary to the said serrations in the bore, and at least one compression spring attached to the end portion of the said connecting bar on its face opposite to that upon which said serrations are formed and abutting the inner face of the bore of the associated door handle, said spring biasing the serrations of the said connecting bar and of the said door handle into engagement.

These and other features of my said invention will become apparent from the following description of an embodiment thereof given by way of example with reference to the accompanying drawing, in which:

FIG. 1 is a plan view, partly in section, of the device,

FIG. 2 is a perspective view of the connecting bar,

FIG. 3 is a broken plan view of one end of the connecting bar illustrated in FIG. 2 shown on an enlarged scale.

FIG. 4 is a perspective view of a variant form of the connecting bar,

FIG. 5 is a plan view, partly in section, similar to FIG. 1, showing a variant form of the device, and

FIG. 6 is a semi-diagrammatic end view of still another form of connecting bar.

As shown in FIG. 1, on both sides of the door 1 a door handle 2 is arranged, each being rotatably journalled with its round stem 3a in a facial disc 3 fixedly connected to the door. Each door handle 2 has a bore 4 of square profile, one face of which, preferably the one nearest the grip of the door handle, is provided with serrations 5. The latter may be cast in, rolled in, or arranged in a ledge 6 inserted and fixed within the bore 4.

The connection of the two door handles is effected by the connecting bar 7, over the ends of which the same are pushed. The connecting bar has likewise a rectangu-

2

lar, preferably square profile and is provided on one face with two groups of serrations 8, one adjacent each of its ends. With the door handles pushed over the ends of the connecting bar, the serrations interengage one another, a compression spring, e.g. designed as a leaf spring 9, assuring this engagement at each end of the bar. As will be seen in the drawing, these leaf springs lie each in a recess 10 of the connecting bar 7 and are fixedly attached to the bar by a rivet 11 or the like. The leaf springs have an outwardly cambered shape and are pressed against the connecting bar when the door handles are pushed over the same. Thereby, automatically, the serrations 5 and 8 are forced into one another and the connecting bar and the door handles are connected with one another with a good fit, which is due particularly to the form of teeth (FIG. 3) chosen.

For detaching a door handle 2, the grip thereof is firstly gripped with the whole hand, and by a pressure towards the door 1 in the direction of the arrow I the spring 9 in this door handle is completely pressed on to the connecting bar. Such motion of the door handle also pivots the handle about its lowermost contact with the facial disc 3 to raise the connecting bar 7 and disengage the serrations 5 and 8. As a result of this disengagement, the handle may be pulled off of the connecting bar by pulling it away from the door in the direction of the arrow II while holding it in the position just described.

Practical tests have shown that when opening and closing the door a pressure in the direction I and a pull in the direction II are never applied to the door handle at the same time. Accordingly the possibility is excluded that the door handle may be pulled off the connecting bar inadvertently.

From the foregoing it is clear, that the door handles and the connecting bar can be connected with one another without the use of any tool, and can be separated from one another in the same way. This is an essential economic advantage, particularly when it is taken into consideration that this work can now be carried out in much shorter time than hitherto. Moreover in known securing devices, as experience has shown, the screws or pins serving as securing means are often lost and have to be replaced.

The serrations 8 of the connecting bar 7 may be stamped or pressed upon the bar, or the bar may be cast with the serrations upon it; or the serrations may be pressed into a separate ledge 14 (FIG. 4) to be attached to the connecting bar. It is also possible to connect the connecting bar 7 at one end fixedly to one door handle 2, and to provide it with serrations and a spring at the other end only (FIG. 5). In certain circumstances serrations 8 and leaf springs 9 may also be provided on two faces (FIG. 6). Instead of a door handle of course a round or olive-shaped door knob may be used.

While I have described herein and illustrated in the accompanying drawings what may be considered typical and particularly useful embodiments of my said invention I wish it to be understood that I do not limit myself to the particular details and dimensions described and illustrated; for obvious modifications will occur to a person skilled in the art.

What I claim as my invention and desire to secure by Letters Patent, is:

1. A door handle assembly, comprising in combination: a pair of door handles each having a stem provided with a bore having at least one row of transverse serrations in the bore, a connecting bar having serrations complementary to the serrations in the bore in each door handle, and at least one compression spring attached to each end portion of said connecting bar on its face opposite to that upon which the serrations are formed and abutting the inner face of the bore of the associated door

handle, said spring biasing the serrations of said connecting bar and of said door handle into engagement.

2. A door handle assembly as claimed in claim 1, wherein the said compression spring is attached to said connecting bar at each end and is a leaf spring.

3. A door handle assembly as claimed in claim 1, wherein the said connecting bar has a square profile, two of said rows of serrations being provided on the same face of the said connecting bar, each of the said door handles being provided with complementary serrations capable of being pushed over the said rows of serrations at each end of the connecting bar.

4. A door handle assembly as claimed in claim 1, wherein the rows of serrations of said connecting bar and said bore are provided upon ledges, and said ledges are fixedly attached to the longitudinal side portion of said connecting bar and within the bore in the stem of each said door handle, respectively.

5. A door handle assembly comprising a door handle formed with a stem having a rectangular bore, a connecting bar of rectangular cross-section adapted to pass through the door and to enter the rectangular bore in the stem of said door handle, said handle having in the bore of its stem a series of transverse serrations formed on each of two adjacent longitudinal faces in the bore, and an end 20

5

portion of said connecting bar having a series of transverse serrations on each of two adjacent longitudinal faces thereof adapted to engage the respective series of serrations in the bore in the stem of said handle, a compression spring attached to the end portion of said connecting bar on its face opposite to one of its faces having serrations thereon, and a second compression spring attached to the end portion of said connecting bar on its face opposite to the other of its faces having serrations thereon, whereby said handle may be pushed over the end of said bar and said springs will hold the series of serrations in said bore in contact with the respective series of serrations on said bar, and whereby radial movement of said handle with respect to said bar may compress said springs, permit disengagement of said serrations, and permit removal of said handle from said connecting bar.
